UNITED STATES PATENT OFFICE.

FRANK B. COMINS, OF NEWTON, MASSACHUSETTS, ASSIGNOR TO AMERICAN MOISTEN-
ING COMPANY, OF BOSTON, MASSACHUSETTS, A CORPORATION OF MAINE.

CONTROL MEANS FOR REGULATING THE OUTPUT OF ATOMIZERS AND THE LIKE.

Application filed March 6, 1924. Serial No. 697,365.

This invention relates to improvements in control means for regulating the output of an atomizer and the like. More especially it provides an improved rotary 5 worm pump adapted, while running at uniform speed, to lift water from a well in varying quantities, dependent upon and controllable by varying the level at which the supply in the well is maintained. The capacity of devices of this sort heretofore proposed, has been a substantially fixed rate for any given speed of pump rotation, except in so far as the capacity may be changed by stopping the pump and resetting a valve thereon which governs the admission of water to the lifting means. Accordingly, in the application of these devices to humidifying apparatus, where the rate at which water is introduced into the atmosphere is of paramount consideration, the worm pumps heretofore known have not been characterized by that regulability of output desirable in apparatus of this sort, with possibility of control while the apparatus as a whole is in operation.

It is among the objects of the present invention to provide apparatus which has a regulatable lifting output, adapted to be controlled entirely by changing the level of the supply from which it pumps. It follows from this, that by devices already known, the rate of a system of humidifiers, located at intervals throughout a considerable area, can be controlled from a single place, without the necessity of visiting each to regulate it, or of operating them at an excess rate with intermittent periods of cessation of humidifying action while the excess becomes absorbed. Another object is 40 to provide a pump of the character described that will be self cleaning and thereby free of any danger of becoming clogged while in use.

These objects are attained by providing a controllable level of supply water and a worm pump of helical form, whose radius increases as its convolutions progress upward, from the inlet or lower end of the pump, in the direction of delivery. Surrounding the worm is a sleeve which preferably is more or less conical and which turns with the worm, preventing water from being thrown out laterally therefrom by centrifugal force, and serves as a part of the conveyor for the water. In the par-

ticular application of the invention illustrated, the water is delivered by the pump and conveyor to the under side of the horizontal rotor of a humidifier. The sleeve is belled outward at its upper end, toward the adjacent under surface of this rotor. The bottom of the sleeve is closed, except for an opening which is provided there for entrance of water, and is immersed in a well.

The level of water in the well may be regulated in any convenient manner, as by a supply tank having a ball float control adjustable to any desired level within a certain range, which tank may be connected to supply a considerable number of humidifier wells, keeping the water in all of them at the adjusted level, which signifies, in each case, at a certain level in the space within the well and outside of the sleeve which is immersed therein, when the apparatus is not operating. By varying the level of the water the effect is gained of a varying depth of immersion of the sleeve in the water; and by this means the amount of water fed by the pump to the rotor is readily controlled. Assuming that the entrance opening for water in the bottom closure of the sleeve is at the level of the surface of the water in the well, or an infinitesimal amount below it, the rotation of the pump will lift the water which enters through that opening but will cease taking water as soon as the well level has fallen to below the opening so that the water seal thereof is broken; and the taking of water will begin again as soon as enough more water has been supplied to raise the level. In practice this would probably happen very quickly through the supply pipe, but as the difference of level between this slightly lowered surface of water in the well and the tank supply level is only infinitesimal, the rate of flow would be relatively slow;

and at any rate the quantity of water flowing through the opening into the worm would always be small and would represent the minimum capacity at which the pump can be operated, it being assumed that the pump is being rotated at a high speed by a motor on its shaft. However, if the level of water in the well be maintained at a head of one inch, for example, above the opening, equivalent to immersion of the sleeve to that depth, there will be a head of water immediately at hand for

replacing such water as passes through the opening into the well. Assuming that the said opening has a size restrictive, so that the cross section is less than that of the worm, the amount of water which flows in through the opening under this head of one inch will be greater than where the head is zero as above assumed; and it will be less than if the head were two inches, which may be taken as another variant level, for example. Thus by varying the level of water in the well the operative head pressing water through the restricted orifice in the bottom of the sleeve is varied at will; and thus the output from the pump to the rotor is controlled. Meanwhile, owing to the conical nature of the construction, any lint, and especially any matted masses of lint which may have gathered in the well and gotten into the worm, is carried forward therethrough freely without clogging it, because, owing to the cone shape, there is a constantly increasing size of passage through the pump. In practice it is observed that although the water level may be one or two inches above the bottom entrance orifice of the sleeve when the apparatus is not rotating, the level in the well tends to sink to the level of this bottom opening when the apparatus is working; but the principle above stated applies equally, with the head being furnished through the supply piping from the distant level-controlling supply tank.

It is intended that the patent shall cover, by suitable expression in the appended claim, whatever features of patentable novelty exist in the capacity control features of the invention.

In the accompanying drawings:

Figure 1 is an elevation in medial section, of apparatus embodying the present invention; with the level control means being shown somewhat diagrammatically on reduced scale;

Figure 2 is a similar elevation of a modified form of sleeve; and

Figure 3 is an elevation showing the details of the water level control means.

Referring to the drawings, 10 designates a rotor of a vertical humidifier, fast on a shaft 12 having connection with some form of power source (not shown) for effecting its rotation; and 14 is the bottom or pan of the humidifier, whose central portion forms a supply well 16 from which water is to be lifted to the rotor, and to which the drippings on the pan may drain. Water is supplied to the well through a pipe 17 threading into its bottom opening 18 and leading from any controllable source, preferably a tank 19, having a ball float 20, placed at about the same level as the well. By means hereinafter described, the controlling position of this float can be varied

to regulate, as desired, the level of the water in the tank 19, and consequently in the well 16.

Depending within the well from the end of the rotor shaft 12 is a worm pump comprising an extension 23 of the shaft having a helical worm thread 24 thereon whose edges have a slight spiral component, as they extend farther from the shaft's axis as the threads progress upward toward the rotor. A sleeve, 25, more or less conical, is fitted around these edges and at the top 25' is belled outward toward the rotor. At the bottom of this sleeve is an opening 26 to permit water to be fed to the worm pump, according to the head maintained above the level of the opening, by the float tank apparatus 19 or other means employed for this purpose. This opening is sufficiently large to pass enough water to supply the maximum delivery when the maximum head for which the apparatus is suited is employed, and yet is so small that the degree of head will make a difference in the amount of flow through it. The sectional area of the spaces ⁷⁰ _a between the threads being larger than this opening, and being of gradually increasing size, due to the cone shape, any foreign matter passing through the opening will have ample freedom in the larger spaces ⁷⁵ _a between the threads to pass out of the pump with the water. An annular baffle 28 may be fixed between the well and the sleeve, to prevent any water which drains along the pan from striking the sides of the sleeve at ⁸⁰ a height from which it might be carried upward on the outside of the sleeve and thence be discharged to the rotor.

In Figure 2 a modified form of sleeve is shown which is partly conical and partly cylindrical. The cylindrical portion 25^a extends from the bottom upward to about the maximum height to which the water level rises in the well, and the conical portion 25^b is from the upper end of the cylindrical portion to the belled top 25'. This form of sleeve has been found advantageous where the rotative speed is such that if the cone extended below water level some of the water surrounding it would be carried up on the outside surface thereof and be discharged onto the rotor. The vertical wall of the cylindrical portion does not so lift the water about it, and consequently the only water delivered to the rotor is that which passes through the interior of the sleeve. If an annular space exists, as illustrated, between the edge of the worm's convolutions and the inner wall of the cylindrical portion, that does not appreciably effect the work of the pump, for even though it does permit of a falling back over the edge of some of the water lifted, this loss is incidentally compensated for by the slight raising of the level of the supply, above that at which it ⁹⁰ ₁₀₀ ₁₀₅ ₁₁₀ ₁₁₅ ₁₂₀ ₁₂₅ ₁₃₀

would otherwise stand when the operator sets the level of supply tank at whatever point gives the desired humidifier output.

Assuming the rotative speed of the pump to be constant, the amount of water which it can lift is dependent upon the depth of immersion of the worm, i. e. upon the head effective to feed water through the bottom sleeve opening. As the pump rotates, water is lifted along the incline of the worm, and gradually begins to rotate and be thrown outward laterally against the inner surface of the sleeve by centrifugal force. When it reaches the upper end of the worm, the water continues upward on the inner wall of the sleeve and finally, at its termination, leaps across the small space between the edge of the latter and the rotor, after which it continues on the rotor, under the influence of centrifugal force, to the fog generating means of the humidifier. When the supply level is low only a small quantity reaches the thread surface, but if the supply level is raised a greater amount is lifted. In consequence, the output of the pump at any instant is dependent upon the height of the water in the well or supply, so that by controlling the latter the output of the pump is regulated. By keeping the supply level constant and the rotative speed unchanged, the amount of water delivered to the rotor will remain the same. Without stopping or altering the pump speed, and without visiting the several humidifiers the pump delivery of each may be varied, by merely altering the level of the supply to change the effective head above the sleeve opening 26. Thus the capacity of the pump may be varied while the humidifier continues in operation.

In Figure 3 is shown a device for controlling the supply level, comprising a plunger valve 22, subjected constantly to supply pressure tending to open it, and a float adjuster 21 pivotally mounted on the valve at 21' having suitable connection with the plunger so that when swung upward about its pivot the plunger is seated and the valve closed. The stem 20' of the float 20 is movable within a hollow in the under side of the adjuster about a pivot screw 31. Its limit of swing upward, with respect to the adjuster, is determined by the setting of the screw 30 which threads through the adjuster and bottoms on the stem. According-

ly if this screw is turned inward, the float 55 is thereby set downward so that when raised by the water in the tank it will engage the valve operatively, to close it, at a lower level of water than it would if the screw had been set higher. In consequence the 60 supply is maintained at any desired level according to the setting of screw 30.

Another method of control is found in the valve 31 set in the line of supply. If this be partly closed, so as to restrict to a desired 65 degree the flow of water to the humidifier, the supply to it may be regulated to anything less than the maximum which the level in tank 19 would provide, thus getting an effect of lowered head on the opening 26 70 in the bottom of the pump sleeve, so long as the pump is operating and constantly removing water from the well. The differential, between the draft of water from the well by the pump, and the supply to the 75 well by return drainage from the pan 14 and fresh supply through the valve 31, under head of the level in tank 19, then constitutes the factor which determines the 80 amount that will flow in through the opening 26 to be lifted. Where the supply comes through a reducing or flow restricting valve, as 31, it may be more accurate to speak of this differential as a "virtual" head of liquid 85 pressure at the inlet opening 26, but it will be understood that in either case reference is made to the variations of pressure with which the water is pressed into the inlet opening.

I claim as my invention:

Means for lifting liquid from a supply to the rotor of a humidifier or the like, comprising a rotatable shaft having a helical worm thread and a housing therefor, having an opening below the level of the supply, for admission of liquid to the space between the convolutions; said opening being of such small area and so arranged that under the working head it does not admit as much water as the worm can lift, so that a variation of head of the water to which it is exposed makes material variation in the amount of water that flows through the worm, thus regulating the output of the 100 humidifier.

Signed at Boston, Massachusetts, this first day of February, 1924.
